UNITED STATES PATENT OFFICE

2,509,535

DISPLAY DEVICE

Aladdin P. Selover, Pocatello, Idaho

Application April 26, 1948, Serial No. 23,265

1 Claim. (Cl. 40—126)

1

This invention relates to a display structure and, more particularly, but not necessarily, to a portable, motivated, display structure.

Various and sundry types of advertising devices have heretofore been proposed for use in store windows and the like, so constructed that one or more parts thereof are normally in motion. It has long been recognized that the movement of an article on display more quickly attracts the eye of a passerby than a stationary article on display. It follows, therefore, that when a person is once attracted to the attention of an article on display by the movement thereof, such person or persons usually linger sufficiently to observe the cause of such motion. The time utilized by the passerby in observing the nature of the movement is ample to convey to the passerby the nature of the article being advertised. One of the objections to general and wide usage of prior motivated advertising or display devices is their prohibitive cost. Also, such devices are stationary and cannot be readily moved from one window to another or from place to place without involving considerable time and expense. It is, therefore, a primary object of this invention to provide a portable, motivated, display device that will be economical to produce and warrant its very broad usage.

Another object is to provide a portable motivated, display device particularly adapted for use in displaying jewelry containing brilliant gems, such as diamonds, whereby different views of such gems and the brilliancy flowing from such views may be progressively observed by an observer.

Another object is to provide a display device of the character described which may be standard in size, and may be moved easily and readily from place to place, as desired.

A further object is to provide a display device having the above characteristics that may be assembled into a compact, composite structure that will eliminate the assembly of parts at the ultimate destination where the display is to be provided.

It is a further object to provide a self-contained and assembled, motivated, advertising, display unit which may be readily placed on and removed from a supporting surface of any display window or other location.

Still another object is to provide a unitary, self-contained and assembled, motivated, advertising unit of simple design, economical to manufacture, requiring a minimum amount of main-

2

tenance and allowing ready accessibility to the operating parts.

The above and other objects will be made apparent throughout the further description of the invention when taken in connection with the accompanying drawings, wherein like reference characters refer to like parts. It is to be understood that the drawings are not a definition of the invention but merely illustrate a preferred form by means of which the invention may be effectuated.

In the drawings:

Fig. 1 is a three-quarter perspective view of a display device embodying the invention.

Fig. 2 is a top plan view of the device illustrated in Fig. 1 having a portion of the top broken away in order to illustrate the construction details of the invention.

Fig. 3 is a sectional view taken along the line 20 III—III of Fig. 2.

Fig. 4 is a perspective view of a detail embodying the invention.

The exemplary form shown in the drawings, comprises a box-life enclosure which may be of any suitable shape and, as here shown, rectangular in shape. The enclosure consists of a bottom 10, front and rear side walls 11 and 12, respectively, end walls 13 and 14, and a removable cover or top 15. The front and rear side walls 11 and 12 and end walls 13 and 14 are recessed adjacent their upper, inner edges, as shown at 16, for receiving flanges 17 projecting downwardly from the side and end edges of the top 15, as clearly depicted by the drawings. The flanges 17 fit into the recesses 16 to form a finished structure and to provide means for releasably maintaining the cover 15 in assembled position.

Within the enclosure is provided a horizontally disposed shaft 20 turnably supported in spaced, vertical flanges 18 and 19 projecting upwardly from the ends of a base member 21, the latter being supported and fixed to the bottom 10 of the enclosure by any suitable means, such as screws 22. Suitable bearings 23 may be disposed in aligned openings within the flanges 18 and 19 for turnably supporting the shaft 20. The forward end of the shaft 20 may be provided with an enlarged portion 24, forming a shoulder 25 for engagement with the opposing surface of the flange 18 adjacent the bearing 23 for limiting the rearward end movement of the shaft 20, while the rear or free end of the shaft 20 may be provided with a washer 26 or other suitable means for limiting the forward endwise movement of the shaft 20. Fixed to and carried by the end of the

50

enlarged portion 24 of the shaft 20 is provided a bracket, represented in its entirety by 27 (see Fig. 4). The bracket 27 may consist of cross members providing four clamping arms 28, the free ends of which terminate in outwardly extending flanges 29 for engagement with the inner end of a manikin or other supporting element, indicated in its entirety by 31. The element 31 is arranged to extend through a recess 32 provided in the central upper portion of the front wall 11. The recess 32 is of sufficient dimensions to permit free oscillation or rotation of the element 31.

In the present embodiment, the manikin 31 consists of an artificial hand having a wrist portion 30 and a hand portion, including the five fingers, as clearly depicted by the drawings. The hand portion and adjacent portion of the wrist 30 extend outwardly from the front wall 11, and the forefinger 33 and thumb 34 of the hand are positioned so that the tips of the fingers 33 and thumb are spaced apart and in gripping relation with a releasable clip member 35, which may be any suitable spring-actuated holding clip, the clip 35 being fixed to the opposing portions of the tips of the fingers 33 and 34. An article, which may be a ring 36, having set therein a diamond 37, is releasably carried by the clip 35. For the purpose of ornamentation and appearance, the wrist 32 may be provided with a cuff, indicated at 38, for obscuring the opening 32 in the front wall 11 and giving the hand 31 a normal dressed appearance. It can now be understood that the hand 31 is supported by and turnable with the shaft 20. Power means is provided for oscillating the shaft 20, which means may consist of any suitable, low-speed unit and, as here illustrated, a low speed electric motor 41 mounted on the bottom 10 of the housing. A suitable transformer, not shown, may be provided for reducing the current to a minimum for driving the motor 41, the amount of current required being negligible.

The motor 41 is provided with a shaft 42 having mounted on the free end thereof of a circular disc 43, the latter having a stub shaft 44 positioned adjacent the periphery thereof and having its axis lying in a plane perpendicular to the plane of the disc 43. For oscillating the bracket 27 and the hand 31 carried thereby, there is provided a link or arm 45 having one of its ends turnably connected to the stub shaft 44, as shown at 46, the other end of the arm 45 being turnably connected to a stub shaft 47 projecting inwardly from one of the arms 28 of the bracket 27 and positioned adjacent the outer end thereof so that upon rotation of the disc 43 by the motor 41 the bracket 27 will be oscillated through an angle corresponding to the radius of the stub shaft 44 with the motor shaft 42.

As here illustrated, the hand 31 will be oscillated through an angle of substantially 45 degrees, although the disc 43 may be of such dimensions as to carry the stub shaft 44 for satisfactorily oscillating the hand 31 through angles from 1 to 170 degrees.

Conductors 48 are provided for connecting the motor 41 to any available source of power, the conductors 48 being connected with a conven-

tional plug, not shown, for engagement with a receptacle connected to a conventional electrical supply circuit.

The enclosure may be of any selected shape or design and the top thereof may also be utilized for displaying stationary articles as indicated in the dotted lines 51 in Fig. 1.

Accordingly, there is provided a portable, motivated, display device wherein the brilliancy of jewelry, such as rings or other articles, may be attractably displayed so as to present different views of the article being displayed. In the case of displaying brilliant jewels, such as diamonds in the show window, the movement of such jewels to present different angles thereof to the usual display lights in the show windows greatly augments the brilliancy of the gems from different angles and the scintillation of the gems quickly attracts the attention of a passerby.

The present device is portable and can be easily and quickly moved as a unit from one place to another. The device may be assembled and shipped as a compact unit. Moreover, the device is simple in design, composed of few parts, economical to manufacture, inexpensive to operate and requires a minimum amount of maintenance. Easy access is provided to the operating parts for inspection and repair.

While I have illustrated and described the preferred form of the present invention, it will now be apparent to those skilled in the art that certain changes, additions, modifications, substitutions and omissions may be made in the form shown without departing from the spirit and scope of the invention as defined by the appended claim. The ring, bracelet, or other article of jewelry may be mounted upon or carried by the hand in various ways.

I claim:

46 A display device comprising: a housing provided with a ported front wall; a shaft rotatably journaled within and contained within the housing, said shaft being in substantial alignment with the port in the wall of the housing; a releasable connecting means mounted on one end of the shaft adjacent the ported wall; an element in the form of a hand carried by the connecting means and extending through the ported wall of the housing; said element being arranged to 45 releasably hold an article to be exhibited; a motor within the housing; and means operably connecting the motor and shaft for repetitively, partially rotating the shaft and element attached thereto, whereby an article held by the element is positioned at progressively different angles for observation by an observer.
